UNITED STATES PATENT OFFICE.

EMIL F. MILLER, OF MENDOTA, ILLINOIS, ASSIGNOR TO FRANK HENNING
AND JACOB HUSS, OF MENDOTA, ILLINOIS.

SWING.

SPECIFICATION forming part of Letters Patent No. 733,913, dated July 14, 1903.

Application filed September 27, 1902. Serial No. 125,074. (No model.)

To all whom it may concern:

Be it known that I, EMIL F. MILLER, a citizen of the United States, residing at Mendota, in the county of LaSalle and State of Illinois, have invented certain new and useful Improvements in Swings; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to swings having chairs hung from a frame and adapted to be put in motion by the occupants exerting pressure on the back and foot rest.

The object of the invention is to form an improved swing of the kind stated.

A further object is to so form such a swing that the seats will not tip when swung.

Further objects and advantages will be apparent from the following description and the accompanying drawings, in which—

Figure 1 is a perspective view of the swing. Fig. 2 is a detail in side elevation, showing a child's bed-platform hung between the seats.

Referring specifically to the drawings, 6 indicates the wooden sills on which the swing is supported. The seats 7 are oppositely disposed, as usual in swings of this kind, and are hung by hangers 8 to swing from and between rectangular frames 9, which in turn are swingingly hung by hangers 10 from supports 11 on the sills. These supports are conveniently formed of tubing bent to circular form, as shown, and supported upon the sills by castings 11^a, which are braced and spaced by cross-rods 11^b.

The hangers 10 extend from the top of the supports 11 to the bottom of the frames 9, and the hangers 8 extend from the top of the frames 9 across under the frames of the seats 7, loose or pivotal joints being formed between the hangers and the supports and frame to permit the desired swing, as will be understood. In consequence of this construction the chairs are hung by the hangers 8 to swing or rock with respect to the frames 9 and also by means of the hangers 10 to

swing with respect to the supports 11, whereby during the operation of the device the seats will remain level. Furthermore, in case it is not desired to use the device as a whole, the seats can be actuated upon the hangers 8 to give a short swing or rock without movement of the supporting-frames 9. The seats are provided with suitable backs 7^a and arms 7^b. The frames 9 are braced under the seats 60 by cross-rods 9^a and by cross-rods 9^b at the bottom.

The foot-rest is formed of side bars 12 and wooden slats 13 between, the ends of the cross-bars being pivotally joined to the frames 9, as by bolts 12^a. The foot-rest is adjustable vertically to suit the users of the swing by means of a series of holes 12^b in the frame to receive said bolts. The foot-rest and its frames 12 are arched or inclined upwardly from both ends to the middle, so as to give a better foothold for pushing the swing than if the foot-rest were level.

A canopy is indicated at 14, supported by standards 15, rising from the circular supports. To assist the swinging operation, I employ springs 16, joined to the seat-frame and the frames of the foot-rest, which serve by their extension during the swinging operation to assist the continuation thereof.

The construction described whereby the seats are permitted to hang loosely and swing in their supporting-frame avoids racking or strain on the frame and because the seats remain level the swing may be safely used by 85 children, as they are not caused to fall out. Each seat may be used independently, if desired, to swing in its own pair of supporting-frames.

Stops to safely limit the movement of the swing are formed by slotted pieces 17, which are pivoted to the frames 9, and the slots receive pins 12^c on the foot-platform 12. The chairs will not swing beyond the distance allowed by the movement of the pins in the 95 slots.

To form a child's bed in connection with the seats I use a removable platform 18, having hooks 18^a at the ends, which may be hooked over the rods 18^b under the front edge 100 of the chair-seats. The platform is of sufficient length to spread the chairs enough to

bring them from their normal tilted position to a substantially level position, as shown in Fig. 2. A comfortable swinging bed for a child may thus be made.

5 What I claim as new, and desire to secure by Letters Patent, is—

1. A swinging chair having at each side supporting means comprising a stationary support, a pair of hangers pivoted at the top 10 to said support, a frame pivotally connected at the bottom to said hangers, and another pair of hangers pivoted at the top to the frame and at the bottom to the chair.

2. The combination in a swing, of the supports, hangers swingingly hung therefrom, 15 chair-frames pivotally connected to the hangers, oppositely disposed chairs swingingly

hung from the frames, and a foot-platform pivotally joined to the chair-frames, substantially as described.

3. The combination in a swing, of side supports, hangers swingingly hung between the same, chair-frames pivotally connected to the hangers, and a chair swingingly hung from and between the frames, by hangers depending from the top of the frame, substantially as described.

In testimony whereof I affix my signature in presence of two witnesses.

EMIL F. MILLER.
